Inventor:
Hale E. Hawk

UNITED STATES PATENT OFFICE.

HALE E. HAWK, OF KANSAS CITY, MISSOURI.

CAR-COUPING.

SPECIFICATION forming part of Letters Patent No. 278,334, dated May 29, 1883.

Application filed February 23, 1883. (No model.)

To all whom it may concern:

Be it known that I, HALE E. HAWK, a citizen of the United States, residing at Kansas City, in the county of Jackson and State of Missouri, have invented certain new and useful Improvements in Car-Couplings; and I do hereby declare that the following is a full, clear, and exact description of the invention, which will enable others skilled in the art to 5 10 15 20 25 30 35 40 45 50 55 60 65 70 75 80 85 90 95 100 which it appertains to make and use the same, reference being had to the accompanying drawings, forming part of this specification.

My invention has for its object a novel combination and arrangement of self-coupling devices for adaptation to the draw-head of a car when provided with the mechanism as described and claimed in my application of January 15, 1883, and also in a novel combination and arrangement of the shackle without necessitating a change in the construction of it, which will self-act upon the coupling devices upon the car to elevate the bolt and couple its relative parts; and it consists, first, in the mechanism upon the draw-head which operates to elevate the bolt, and permits, also, an independent movement in the releasing of the coupling devices; second, in the novel arrangement of the shackle for elevating the coupling-bolt.

In the drawings, Figure 1 is a vertical sectional view of the draw-head and coupling mechanism with the shackle in position to enter the draw-head. Fig. 2 is a side elevation of the draw-head and coupling devices thereon. Fig. 3 is a front view of the draw-head and coupling mechanism. Fig. 4 is a top view of shackle and self-coupling devices thereon. Fig. 5 is an end elevation of the same.

A represents a draw-head of a car. B is a coupling-bolt. C is a lifting-bar of a suitable width, arranged across the draw-head, and having suitable perforations to admit the bolts. D D are lifting-bolts secured to bar C by nuts d. E is a rock-shaft on guide-box G. F is a lifting-arm on rock-shaft E. G is a guide-box attached to draw-head A. H is an arm adjustably arranged on bolt D by screw h, and g is a wrist upon said arm. K is an angle-iron attached to guide-box G by nuts d d. P is a 50 tripping-lever on rock-shaft E. M is a com-

mon and well-known shackle. O is a self-adjusting arm attached to shackle M by a vertical bar, N, and having cross-bar o.

In the construction of my invention I arrange in a transverse relation to and beneath the draw-head in guide-box G a rock-shaft, E, and secure said shaft from lateral play by suitable bolt-heads or other retaining devices. A lifting-arm, F, is then arranged upon the rock-shaft E, between the lifting-bolts D D and the 60 guide-box G. Upon the lower end of the bolts D D, I arrange an arm, H, in the same vertical relation thereto, and adjust said arm upon the bolts at any varying height by the screw h. At right angles to and at the upper end of the 65 adjustable arm H, I attach a wrist, g, in line with the lifting-arm F on the rock-shaft E, by which arm the adjustable arm H and lifting-bolts D D are elevated. Upon the rock-shaft E, and midway of the same, I arrange a tripping lever, P, of sufficient length to meet the cross-bolt o of the self-adjusting arm of the shackle. In advance of the shackle M, and connecting the two opposite portions of the self-adjusting arm O together, is the cross bolt or bar o, 70 which meets the depending tripping-lever P on rock-shaft E, and communicates a partial rotation to said shaft and a rear movement of the lifting-arm F against the wrist g of the 75 vertical and adjustable arm H, attached to the 80 lifting-bolts, by which operation the said lifting-bolts are raised, and also the coupling-bolt, from their ordinary position when coupled. The cross bolt or bar o, in its contact with the tripping-lever P, acts to throw the same in 85 rear until past its radiate length, when it instantly falls to a vertical position, releasing the support to the adjustable arm H and permitting the fall of the coupling-bolt, the position of the shackle at the moment of the 90 releasing of the tripping-lever being within the draw-head and past the coupling-bolt, whereby the shackle is retained.

In the adaptation of my invention, particularly to freight-cars, the releasing of the 95 shackle, either from accident or by lifting devices upon the car, permits the self-adjusting arm to be withdrawn, the lifting-arms being arranged to act independently of the lifting-bolts, whereby the tripping-lever swings out.

wardly on the cross-bolt of the self-adjusting arm until past its length, when said lever falls to its usual or vertical position.

Having fully described my invention, what I now claim, and desire to secure by Letters Patent, is—

1. In combination with the draw-head of a car provided exteriorly with a suitable guide-box arranged beneath and extending beyond the opposite sides of said draw-head, and oppositely-arranged lifting-bolts in said guides, which are connected with the coupling-bolt, a rotary shaft arranged transversely within said guide-box and beneath said draw-head, and provided with suitable extensions to engage with the lifting-bolts and for operating the shaft, substantially as described.
2. In combination with the draw-head of a car provided exteriorly with a suitable guide-box arranged beneath and extending beyond

the opposite sides of said draw-head, and oppositely-arranged lifting-bolts in said guides, which are connected with the coupling-bolt and provided with an adjustable arm and wrist, a rotary shaft arranged transversely within said guide-box and beneath said draw-head, and provided with suitable extensions to engage with the wrist upon the adjustable arm of said lifting-bolts, as described.

3. In combination with a self-adjusting arm attached by a suitable bar to and in a parallel relation beneath a shackle, and provided with suitably-inclined ends, a bolt or bar arranged upon and in a transverse relation to said arm, for the purpose specified.

HALE E. HAWK.
